United States Patent Office

Des. 186,235
Patented Sept. 29, 1959

186,235

PLAYGROUND GYM

Isadore Horowitz, Bossier City, La., assignor to Universal Manufacturing Co., Inc., Bossier City, La., a corporation of Louisiana

Application March 3, 1958, Serial No. 49,877

Term of patent 14 years

(Cl. D34—5)

The dominant feature of my new design resides in the portion shown in full lines.

I claim:

The ornamental design for a playground gym, as shown and described.
